CLAIM

The ornamental design for a combined cap holder and cap, as shown and described.

DESCRIPTION

FIG. 1 is a top plan view of the combined cap holder and cap showing my new design;

FIG. 2 is a front elevational view thereof, the rear elevational view being a mirror image thereof;

FIG. 3 is a bottom plan view thereof; and

FIG. 4 is a right side elevational view thereof, the left side elevational view being a mirror image thereof.
